UNITED STATES PATENT OFFICE.

WALTER C. CARLSON, OF MILWAUKEE, WISCONSIN.

DESIGN FOR AN ADVERTISING STAND.

Application filed July 26, 1922. Serial No. 3,205. Term of patent 3½ years.

To all whom it may concern:

Be it known that I, WALTER C. CARLSON, a citizen of the United States, residing at Milwaukee, in the county of Milwaukee and State of Wisconsin, have invented a new, original, and ornamental Design for Advertising Stands, of which the following is a specification, reference being had to the accompanying drawing, forming part thereof.

Figure 1 is a front elevation of an advertising stand embodying my new design.

Figure 2 is a side elevation of the same.

The vertical card is adapted to receive decorative or advertising matter, and the inclined portion may have painted upon it articles of food described in the accompanying advertisement. The arrangement is such that when the device is viewed from the front the inclined portion constitutes a pleasing base for the card.

I claim:

The ornamental design for an advertising stand as shown.

WALTER C. CARLSON.
